UNITED STATES PATENT OFFICE.

ALBERT HENRY HUGGINS, OF CLINTON, WISCONSIN.

DESIGN FOR A CHECKREIN-HOLDER.

SPECIFICATION forming part of Design No. 30,536, dated April 11, 1899.

Application filed February 4, 1899. Serial No. 704,591. Term of patent 7 years.

To all whom it may concern:

Be it known that I, ALBERT HENRY HUGGINS, a citizen of the United States, residing at Clinton, in the county of Rock and State of Wisconsin, have invented and produced a new and original Design for Checkrein-Holders, of which the following is a specification, reference being had to the accompanying drawings, forming a part thereof.

10 I have illustrated my invention in the accompanying drawings, in which I have shown at Figure 1 a side view, and at Fig. 2 a rear perspective view, of my new design.

15 In the views the same part is designated by the same reference-letters.

The shank A of the hook is substantially square in cross-section, and the base B, as shown, is substantially rectangular in shape, being slightly beveled at its rear end b. The 20 upper edges of the base are rounded, and a groove or recess b' is disposed in its rear face, as shown in Fig. 2.

The body C of the hook is disposed and ar-

ranged as shown in the drawings and projects from the front of the base in a curved 25 line resembling in appearance the well-known gooseneck curve. The body is substantially circular in cross-section and decreases in its diameter as it projects to its extremity.

The gravity-latch D is substantially circular in cross-section and has the large rounded head d disposed at its upper end, as shown, where it is connected with the body of the hook. Its opposite end is beveled and somewhat elongated to fit the recess b' of the base. 35

Having described my invention, what I claim as new, and desire to secure by Letters Patent, is—

30 The design for a checkrein-holder as herein shown and described.

40 In testimony whereof I affix my signature in presence of two witnesses.

ALBERT HENRY HUGGINS.
